UNITED STATES PATENT OFFICE.

JOHN E. TIFFIN, OF REDDING, CALIFORNIA, ASSIGNOR OF ONE-HALF TO
WILLIAM A. SMITH, OF SAME PLACE.

COMBINED MOP-HOLDER AND SCRAPER.

SPECIFICATION forming part of Letters Patent No. 253,131, dated January 31, 1882.

Application filed November 14, 1881. (No model.)

To all whom it may concern:

Be it known that JOHN E. TIFFIN, of Redding, county of Shasta, State of California, have invented a Mop and Scraper; and I here-
5 by declare the following to be a full, clear, and exact description thereof.

My invention relates to an instrument or tool which combines in itself both mop and scraper.

10 It consists of an extended shank terminating in a cross-piece, at right angles to which a plate constituting the scraper is pivoted so as to fold horizontally, its natural position being a vertical one, in which position it is secured by a brace extending from its center and curved toward the shank, so as to have its end lie on it and be secured thereto by a slide, as will hereinafter appear.

Referring to the accompanying drawings, 20 Figure 1 shows my device with the scraper in position. Fig. 2 shows it open and ready to receive the mop.

Let A represent the shank, the cross piece B being at right angles to its end, and C the 25 downwardly-projecting arms of the cross-piece B. To the ends of these arms C is pivoted the plate or scraper D, made to turn, and having its lower edge beveled or sharpened, as shown, for scraping purposes. The brace E extends from the middle of the plate D, being curved 30 as shown, and is fastened to the shank A by the slide F. The shank A is fitted to a handle, G, the length of which is determined by the intended use of the tool.

When the tool is to be used as a mop the 35 slide F is slipped back, releasing the brace E, and the plate D is turned into a horizontal position. The rag, cloth, or mop of any kind is then inserted between the plate D and the cross-piece B, and the plate D is then turned 40 back to its vertical position and secured by the slide F. The rag or mop is thus caught and the tool is ready for use.

Having thus described my invention, what I claim as new, and desire to secure by Letters 45 Patent, is—

1. The plate D, journaled in the transverse bar B, so that it may be turned to receive the material of the mop, and having the projecting arm or brace E engaging with the slide F, 50 whereby it may be locked to hold the material in place, substantially as herein described.

2. The combined mop and scraper, consisting of the plate D, having its edge formed into a scraper, as shown, and ends journaled to the 55 bar of the frame, and provided with the arm E, adapted to be held by the slide F, so as to retain the material of the mop, substantially as herein described.

In witness whereof I have hereunto set my 60 hand this 18th day of October, 1881.

JOHN E. TIFFIN.
